US00D952072S

(12) **United States Design Patent** (10) Patent No.: **US D952,072 S**
(45) Date of Patent: **** May 17, 2022**

(54) **BICEP CURL EXERCISE MACHINE**

(71) Applicant: **PELOTON INTERACTIVE, INC.**,
New York, NY (US)

(72) Inventors: **Sean K. Horita**, Woodinville, WA
(US); **Elijah E. Hooper**, Seattle, WA
(US)

(73) Assignee: **Peloton Interactive, Inc.**, New York,
NY (US)

(**) Term: **15 Years**

(21) Appl. No.: **29/720,930**

(22) Filed: **Jan. 16, 2020**

(51) LOC (13) Cl. **21-02**

(52) U.S. Cl.

USPC **D21/690**

(58) **Field of Classification Search**

USPC D21/690, 691, 694, 686, 662, 665, 676,
D21/679, 687, 692

See application file for complete search history.

(57) **CLAIM**

We claim the ornamental design for a bicep curl exercise machine, as shown and described.

DESCRIPTION

FIG. 1 is a front, side perspective view of a bicep curl exercise machine of a fitness equipment unit;

FIG. 2 is a front view of the bicep curl exercise machine of FIG. 1;

FIG. 3 is a rear view of the bicep curl exercise machine of FIG. 1;

FIG. 4 is a first side view of the bicep curl exercise machine of FIG. 1;

FIG. 5 a second side view of the bicep curl exercise machine of FIG. 1;

FIG. 6 is a top view of the bicep curl exercise machine of FIG. 1; and,

FIG. 7 is a bottom view of the bicep curl exercise machine of FIG. 1.

The broken lines and the dot dash lines shown throughout the figure views form no part of the claimed design.

1 Claim, 7 Drawing Sheets
